Primary Examiner — Eric Goodman*Assistant Examiner* — Luqman McNeil(74) Attorney, Agent, or Firm — Cantor Colburn LLP(57) CLAIM

We claim, the ornamental design for a display screen or portion thereof with icon, as shown and described.

DESCRIPTION

FIG. 1 is a front image of a display screen or portion thereof with icon showing our new design; and, FIG. 2 is a front view of another embodiment of a display screen or portion thereof with icon showing our new design. All evenly spaced broken lines illustrate a display screen or portion thereof, and form not part of the claimed design.

1 Claim, 2 Drawing Sheets Fig. 1
